UNITED STATES PATENT OFFICE.

JOHN E. GARDNER, OF CHICAGO, AND JOHN I. BELLAMY, OF BROOKFIELD, ILLINOIS,
ASSIGNORS, BY MESNE ASSIGNMENTS, TO AUTOMATIC ELECTRIC INC., OF CHICAGO,
ILLINOIS, A CORPORATION OF DELAWARE.

AUTOMATIC TELEPHONE SYSTEM.

Original application filed October 9, 1922, Serial No. 593,413, now Patent No. 1,610,438, dated December 14, 1926. Divided and this application filed September 23, 1926. Serial No. 137,217.

The present invention relates in general to automatic telephone systems, but is more particularly concerned with systems of this character employing party lines; and the 5 general object of the invention is to provide a novel and improved party line system in which revertive calls may be made, that is, calls from one subscriber on one line to another subscriber on the same line, in the 10 same manner as ordinary calls by dialling the regular directory number of the desired party.

More particularly it is the object of the invention to provide automatic ringing on 15 revertive calls. To explain more fully, a subscriber desiring to call another party on his own line dials the regular directory number of that party and the connection is established in the usual manner through 20 the regular trunking system. Responsive to the establishment of the connection, automatic ringing equipment is placed in operation and the desired party is signalled in the same manner as if an ordinary call were 25 in progress. When the called party responds the ringing current is disconnected and the talking circuits are established.

An additional object of the invention is 30 to change the circuits of the connector switches, which are used to extend connections to party lines, so that on revertive calls the response of the wanted subscriber brings about the release of the connector switch and selector switches, talking battery 35 being fed to both calling and called subscribers from the windings of the line relay of the first selector.

Another object of the invention is to give 40 the calling subscriber when he makes a revertive call the regular ringing induction to inform him when the desired connection is established.

All the features pointed out above are 45 claimed broadly in the parent application, Serial No. 593,413, now Patent No. 1,610,438 of which this application is a division. In this divisional application, a particular modification will be disclosed and claimed.

Referring now to the drawing, there is 50 shown by means of the usual schematic circuit diagrams, sufficient of the apparatus of the system to enable the invention to be clearly described and understood.

The substation A is similar to the usual automatic type. However, its circuits have 55 been modified so as to enable the same to be used with the present invention. While only the circuits of one substation on the party line have been shown herein, it will be understood that the other substation A' 60 thereon, the ringer of which has been indicated, will be similar to the substation A. The party line terminates at the exchange in an individual line or trunk selecting 65 switch C.

The line switch C is of the usual rotary type whose wipers have no normal position, always standing, when idle, with its wipers in association with the bank contacts of the trunk line last used. This line switch C, 70 in common with a plurality of other line switches, has access to trunk lines leading to first selector switches.

The first selectors have access to trunk 75 lines leading to second selectors and the second selectors in turn have access to trunk lines extending to connector switches, one of these trunk lines being the trunk line shown in the drawings extending to the connector H.

The connector H is of the usual Strowger vertical and rotary type and has access to party lines, one of these being the one comprising conductors 288 and 289 extending to 85 substations A and A'. Its circuit arrangements form a particular part of this invention and will be described in detail hereinafter.

In order to enable each of two parties on the same line to be selectively signalled, 90 harmonic ringing is employed. Two groups of connectors have access to one party line and each group has a different frequency of ringing current associated with it. To signal the desired party on the 95 party line it is only necessary to select a connector in the particular group. This is the scheme of harmonic ringing ordinarily used in automatic systems.

The operation of the invention will now 100 be described in detail. For this purpose it will be assumed that some subscriber desires to call the subscriber at substation A. To accomplish this result the subscriber at the calling substation will remove his receiver and operate his calling device for the 105

5 digits of the directory number of the subscriber at substation A. When the receiver is removed at the calling substation, the line relay of the line switch associated with the line of the substation calling is energized and initiates the operation of this switch in the usual manner. The operations of the calling line switch and the first and second 10 selectors are well known and need not be described. It will be assumed that the connection is extended to the connector H over the trunk line comprising conductors 88'-90', inclusive. The line relay 202 of this switch operates to close the circuit of the slow acting release relay 203. Upon operating, relay 203 prepares the operating circuits of the connector H at armature 232 and at armature 231 places ground upon the release trunk conductor 89' to establish 15 the usual holding circuit for the previously operated switches.

20 In response to the first operation of the calling device at the calling substation the vertical magnet 213 is operated under control of the line relay 202 to raise the switch wipers 260-262, inclusive, step by step, until the wipers are placed opposite the proper level of bank contacts. Slow acting relay 204 is energized in series with the vertical magnet and operated to maintain its armature attracted throughout the vertical movement of the switch, thereby maintaining the vertical magnet circuit closed when the off normal springs are shifted, which operation 25 occurs upon the first vertical step of the switch. Upon deenergizing at the end of the vertical movement, the slow acting relay 204 transfers the impulsing circuit to the rotary magnet 214.

30 When the calling device at the calling substation is operated in accordance with the next and final digit in the desired number the rotary magnet 214 is operated under control of the line relay 202 and operates 35 to advance the switch wipers into engagement with the bank contact set comprising contacts 270-272, inclusive, associated with the line of the substation A. The relays 207 and 208 are energized and function in a manner to be described hereinafter.

40 Assuming that the desired line is idle at this time, the switching relay 209 is energized in series with the switching relay 275. Relay 275 of the line switch C operates to 45 disconnect the line of the called substation from its normal battery and ground connections in the line switch. Relay 209, upon operating, establishes a locking circuit for itself at armature 253 and at armatures 251 and 255 prepares the signaling circuit.

50 Upon the deenergization of relay 208, which was energized in multiple with rotary magnet 214, the signaling circuit is closed. This circuit extends from the generator lead 55 55 to 290 by way of back contact and armature

221, through the upper winding of the ring cut off relay 205, back contact and armature 236, back contact and armature 246, front contact and armature 251, wiper 260, bank contact 270, over the line conductor 70 288, lower right hand winding of the ringer, condenser, lower left hand winding of the ringer, springs of the calling device, line conductor 289, bank contact 272, wiper 262, armature 255 and its front contact, armature 75 239 and its back contact, back contact and armature 222, armature 237 and its back contact, to ground. The ringing current flowing through the lower windings of the ringer at substation A causes the bells to be 80 actuated in the ordinary manner. This ringing current also flows through the ringer at substation A'. However, as a particular frequency of ringing current has been selected by the operation of the second 85 selector to pick out a particular group of connectors, only the bells of the substation A respond. When the receiver is removed, ring cut-off relay 206 is energized over the called line loop and operates to establish a 90 locking circuit for itself at armature 238, and to disconnect the ringing current and to complete the talking circuit at armatures 236 and 239. The back bridge relay 201 is energized over the called line and operates 95 to reverse the connection of the line relay 202 with regard to the incoming trunk conductors for supervisory or metering purposes in the usual manner.

100 The two subscribers may now engage in conversation, and when the conversation is terminated, the release of the connection takes place in the usual manner.

105 If the line of the substation A is busy when the wipers of the connector H' are brought into engagement with the bank contacts 270-272, inclusive, the busy signal is given to the calling subscriber by the operation of the test relay 206 in the well known manner.

110 It will now be assumed that the subscriber at substation A' desires to call the other party at substation A on his own line. In this case the operation is substantially the same as before described. That is, the line switch C, and a first and a second selector are operated to seize a connector such as the connector H. The connector H is in turn operated in the same manner as before, the only difference being that when its wipers 115 are brought into engagement with the bank contacts 270-272, inclusive, the relays 207 and 208 operate conjointly to bring about a reduction of the potential on the test contact 271 in order to energize the switching relay 120 209. This operation is as follows: During the rotary movement of the switch, relay 207 is operated in multiple with magnet 214, and relay 208 is operated, its circuit including armature 245. At the end of the verti- 125 130

cal movement, these relays deenergize in succession, relay 208 maintaining its armatures attracted a short time after its circuit is opened by the release of relay 207. Thus the potential on the release conductor 89' extending through the preceding operated switches and connected to conductor 36 is reduced sufficiently to cause relay 209 to energize. Upon operating, relay 209 establishes a locking circuit for itself and prepares points in the signalling circuit.

Since the receiver is removed at substation A', relay 200 is energized over the calling line loop and operates to establish a locking circuit for itself at armature 240. Other results of this energization are that at armature 221 relay 200 prepares certain points in the signalling circuit, at armature 222 disconnects ground from the wiper 262 and 20 connects it to conductor 89', at armature 223 places ground upon the conductor 256, at armature 224 opens a point in the release magnet circuit, and at armatures 220 and 226 disconnects the line relay 202 from the calling line. Relays 202 and 203 deenergize, which operation effects no particular results at the present time. Still another result of the energization of relay 200 is that a circuit is prepared for the lower winding of the 25 ring cut off relay 205. Upon the deenergization of relay 208, the ringing circuit is completed and also the circuit of the lower winding of relay 205 at armatures 246 and 249, respectively. The ringing circuit may be 30 traced from the generator lead 290' through the alternating current relays 211 and 210 in series, armature 221 and its front contacts, to wipers 260 and 262, thence over the line conductors 288 and 289 in parallel 35 through the lower windings of the bell coils 283 and 284, through the condenser, and through the upper windings of the bell coils to ground by way of switch-hook springs 282. Thus the ringer at substation A is actuated over a simplex circuit which includes 40 the two line conductors in parallel. As this circuit is opened at substation A' by the receiver being off the switchhook, no ringing current flows through the ringer at substation A'. It will be remembered that when 45 the ringing circuit is completed a circuit is also closed for the lower winding of the ring cut-off relay 205. However, the ring cut-off relay does not energize at this time due to 50 the fact that it is slow to operate and that this circuit is immediately opened at armature 240', by the energization of alternating current relay 211. The alternating current relay 210 in series with relay 211 is marginal 55 and is not operated in series with the ringer at substation A. During the time the interrupter relay 294 is in operated position, ringing current from the 16 cycle generator is supplied to the line of the called substation

in order to actuate the ringer thereat. During the silent period, when the relay 294 is deenergized, the 75 cycle generator is connected over the ringing circuit. The ringers at the substations A' and A are adapted not to respond to this frequency and are therefore not actuated. However, the alternating current relay 211 is maintained energized.

When the subscriber at substation A responds by removing his receiver, the previously traced simplex circuit is opened by the operation of the switchhook, and the alternating current relay 211 deenergizes and completes the circuit of the ring cut-off relay 205. Upon operating, relay 205 establishes a locking circuit for itself at armature 238, opens the ringing circuit at armatures 236 and 239, and at armature 237 removes ground from the release trunk conductor 89' and also opens the locking circuit of the relay 200. The disconnection of ground from the release trunk conductor 89' and the deenergization of the relay 200 bring about the release of the connection in the well known manner. The circuit of release magnet 212 is closed at armature 224, and the circuits of relays 205 and 209 are opened by the removal of ground from the holding conductor at armature 223. As the receivers at the substations A' and A on the calling line are now removed the line switch C will operate to seize the selector used in the preceding connection or another selector. Talking battery is now supplied to the subscribers from the line relay of the seized selector. The connection comprising the switches C and the seized selector is released when both receivers are replaced on the party line.

Reconsidering the previous connection, it will now be assumed that the subscriber at substation A did not respond and that the subscriber at substation A' replaces his receiver. Responsive to the latter operation, the ringer at substation A' is included in the simplex ringing circuit and the impedance of the circuit is accordingly decreased thus allowing a greater amount of current to flow through the marginal alternating current relay 210, which immediately energizes and closes the circuit of the ring cut-off relay 205. The energization of the ring cut-off relay 205 bring about the release of the connection in the same manner as has been before described.

It will be seen that by the use of the system shown, it is possible to make a reverting call back to a desired subscriber on the same line as the calling one in the same manner as if an ordinary call were being made to another subscriber and in the case of this reverting call all the switches are released when an answer is obtained with the exception of the line switch and the

first selector, thereby materially reducing the number of switches necessary in the connection.

The features of the invention having been described, what is considered to be new and is desired to have protected by Letters Patent is pointed out in the appended claims.

What is claimed is:

1. In a telephone system, telephone lines, a plurality of stations on each of said lines, a series of selector switches and a connector switch under the control of a subscriber at one of the stations on one of said lines for extending a connection to another station on the same line or to a station on another line, means in said connector switch operative when connection is extended to said same line for applying signalling current over a simplex circuit to signal the desired station, and means in said connector operative when connection is made with another of said lines for applying said signalling current over a series circuit to signal the desired substation on the called line.
2. In a telephone system, telephone lines, a plurality of stations on each of said lines, a series of selector switches and a connector switch under the control of a subscriber at one of the stations on one of said lines for extending a connection to another station on the same line or to a station on another line, means in said connector switch operative when connection is extended to said same line for applying signalling current over a simplex circuit to signal the desired station, means in said connector operative when connection is made with another of said lines for applying said signalling current over a series circuit to signal the desired substation on the called line, and means responsive to the removal of the receiver at the called substation in either connection to disconnect said ringing current.
3. In a telephone system, telephone lines, a plurality of stations on each of said lines, a series of selector switches and a connector switch under the control of a subscriber at one of the stations on one of said lines for extending a connection to another station on the same line or to a station on another line, a relay in said connector switch energized over the called line loop in case the called line is the calling line, and means controlled by the said relay for applying signalling current to the called line over a simplex circuit.
4. In a telephone system, telephone lines, a plurality of stations on each of said lines, a series of selector switches and a connector switch under the control of a subscriber at one of the stations on one of said lines for extending a connection to another station on the same line or to a station on another line, a relay in said connector switch ener-

gized over the called line loop in case the called line is the calling line, means controlled by the said relay for applying signalling current to the called line over a simplex circuit, said relay remaining de-energized when connection is made with another of said lines whereby signalling current is applied to the last mentioned line over a series circuit.

5. In a telephone system, a telephone line having a plurality of stations thereon, an automatic switch controlled from a calling one of said stations for extending a connection to said line, a source of ringing current, and means responsive to the establishment of said connection for applying said source to said line over a simplex circuit.

6. In a telephone system, a telephone line having a plurality of stations thereon, an automatic switch controlled from a calling one of said stations for extending a connection to said line, a source of ringing current, means responsive to the establishment of said connection for applying said source to said line over a simplex circuit, and means controlled over said simplex circuit for disconnecting said ringing current responsive to the removal of the receiver at the called substation.

7. In a telephone system, a party line, a calling and a called station on said line, an automatic switch, means controlled from said calling station for operating said switch to connect with said line, means in said switch for automatically signalling the called station, a first and a second ring cut-off relay in said switch, said first relay being responsive to the replacement of the receiver at the calling station to interrupt the signalling of the called station, and said second relay being responsive to the removal of the receiver at the called station to interrupt the signalling of the called station.

8. In a telephone system, a party line, a calling and a called station on said line, an automatic switch, means controlled from said calling station for operating said switch to connect with said line, means in said switch for automatically signalling the called station, a first and a second ring cut-off relay in said switch, said first relay being responsive to the replacement of the receiver at the calling station to interrupt the signalling of the called station and to effect the release of said switch, and said second relay being responsive to the removal of the receiver at the called station to interrupt the signalling of the called station and to effect the release of said switch.

9. In a telephone system, a party line, a second line, a calling station on said party line, an automatic connector switch, means controlled from said calling station for operating said switch to connect with either of said lines, signalling means in said switch, a

first and a second ring cut-off relay in said switch, and means for connecting said signalling means to the line connected with via either of said ring cut-off relays, depending on whether the line connected with is said party line or said second line.

10. In a telephone system, a line, means for extending a connection to said line, means for applying signalling current to said line, means for increasing said current, means for decreasing said current, and means responsive to either a decrease of said current or an increase in said current for disconnecting said current from said line.

15. 11. In a telephone system, a line, an automatic switch, means for operating said switch to extend a connection to said line, means in said switch for applying signalling current to said line, and means responsive either to a decrease or an increase in said current for releasing said switch.

12. In a telephone system, a line, an automatic switch, means for operating said switch to extend a connection to said line, 25 means in said switch for applying signalling current to said line, a ring-cut-off relay in said switch for disconnecting said current from said line, and means responsive either to a decrease or an increase in said current 30 for controlling said relay.

13. In a telephone system, a line, means for extending a connection to said line, a source of signalling current, a relay, means for intermittently connecting said source in series with said relay to said line to periodically signal the subscriber on said line and to energize said relay, a second source of current, and means for connecting said second source to said line during the intervals that said first source is disconnected therefrom to 35 maintain said relay energized.

14. In a telephone system, a line, means for extending a connection to said line, a first and a second source of signalling current, a signal on said line responsive to current from one of said sources, relay responsive to current from both of said sources, and means for alternately connecting said sources to said line to operate said signal 45 intermittently and to operate said relay continuously.

In witness whereof, I hereunto subscribe my name this 14th day of September, A. D. 1926.

JOHN E. GARDNER.

In witness whereof, I hereunto subscribe my name this 14th day of September, A. D. 1926.

JOHN I. BELLAMY.
